(57) **CLAIM**

The ornamental design for a sensor protective hood, as shown and described.

DESCRIPTION

FIG. 1 is a front, top-left perspective view for a sensor protective hood, showing our new design;

FIG. 2 is a front perspective view of FIG. 1 thereof;

FIG. 3 is a rear elevational view of FIG. 1 thereof;

FIG. 4 is a left side perspective view of FIG. 1 thereof;

FIG. 5 is a right side perspective view of FIG. 1 thereof;

FIG. 6 is a top plan view of FIG. 1 thereof; and,

FIG. 7 a bottom plan view of FIG. 1 thereof.
